GRAIN-SAMPLING MECHANISM

Ferry F. Rosewarne, Lowell, Mich.

Application October 4, 1934, Serial No. 746,824

6 Claims. (Cl. 73—21)

The present invention relates to mechanism for withdrawing from a mass of grain, beans and the like samples thereof simultaneously with the delivery of the mass to containers for storage or shipment, and to means for identifying such samples with the mass from which the same are withdrawn, and to receptacles for the samples adapted to be so applied to said mechanism as to receive such samples only; and the object of the invention is, generally, to provide improved mechanism, means and receptacles of that character and in combinations; and, more particularly, to provide certain forms and embodiments of the invention whereby its purposes may be attained.

These and any other and more specific objects hereinafter appearing are attained by, and the invention finds preferable embodiment in, the structures and devices hereinafter particularly described in the body of this specification and illustrated by the accompanying drawings, in which:

Figure 1 is a top plan view of mechanism for withdrawing samples of grain, beans or the like from a bin or its discharge spout which is shown in horizontal section taken on line 1—1 of Figure 2;

Figure 2 is an elevational front view thereof partially sectioned vertically on line 2—2 of Figure 1;

Figure 3 is an elevational right hand side view of the same, the gate valve being shown in open position;

Figure 4 is a horizontal sectional view thereof taken on line 4—4 of Figure 3;

Figure 5 is a vertical sectional view of the same taken on line 5—5 of Figure 6;

Figure 6 is a vertical sectional view of said mechanism taken on line 6—6 of Figure 5;

Figure 7 is a top plan view of receptacle for said samples and adjacent parts partially sectioned on line 7—7 of Figure 8;

Figure 8 is a vertical sectional view thereof taken on line 8—8 of Figure 7;

Figure 9 is a vertical sectional view of the same taken on line 9—9 of Figure 8;

Figure 10 is a top plan view of parts of said receptacle one of such parts being sectioned horizontally on line 1—1 of Figure 8;

Figure 11 is a like view of said parts in another position;

Figure 12 is a vertical sectional view of parts of said receptacle taken on line 12—12 of Figure 11;

Figure 13 is a vertical sectional view (enlarged)

of parts of said mechanism taken on line 5—5 of Figure 6;

Figure 14 is a view of a paper strip having markings for identifying the samples with the mass of grain from which they were withdrawn.

In the embodiment of the invention illustrated by these drawings, a mechanism is shown for withdrawing samples of grain, beans or the like passing through the discharge spout 1 of the bin of a warehouse, elevator, etc., said spout having a gate valve 2 slideable horizontally in bearings 3, the grain, etc. indicated at 4 resting on this gate in its closed position shown in Figures 1, 2 and passing by gravity out of the bin when the gate is slid outwardly to open position seen in Figures 3, 4. When this gate is opened, the most of the mass of grain falls through the lower portion 5 of the spout and may be received in a suitable vessel or bag 6 for storage or shipment, while a smaller portion of the grain falls through an opening 7 in the upper wall 8 of a cross-sectionally round chute 9 whose inner end 10 having said opening extends into said spout immediately below the gate when closed, as shown in Figure 2.

This chute contains journalled at 11 in its ends a helical conveyor 12 rotatable to feed the grain samples through the chute and through its opening 13 in the right hand end of its bottom wall 14 and thus deliver the samples into a receptacle, the can 15.

The conveyor has a gear 16 on its shaft portion with which meshes a driving gear 17 rotatable on a hollow shaft 18 which is rotatable in bearings 19 in the housing 20. This gear 17 is rotated by a spiral spring 21 whose inner end is secured at 22 thereto and whose outer end is engaged at 23 by an arm 24 of a sleeve 25 rotatable on the hollow shaft 18. A gear 26 turnable on this sleeve 25 has a pawl 27 engaging ratchet teeth 28 on the hub portion 29 of said sleeve so that the spring may be wound up or compressed by the toothed rack 30 meshing with said gear 26 and extending parallel with the gate 2 being mounted at 31 thereon so as to move horizontally therewith in the gate's sliding movement.

When this gate is drawn outwardly so that the grain may fall through the spout, the gear 26 is rotated to wind up the spring. This spring then unwinding rotates the gear 17 and the gear 16 on the conveyor's shaft portion thus causing the conveyor to operate as above explained.

Means are provided for delivering identically marked portions of a paper strip 32 (shown in Figure 14) to the bag 6 containing the mass of grain and to the receptacle or can 15 containing

the samples thereof, as well as to the operator of the mechanism. This strip has sections each comprising a forward main part 33 and smaller parts 34, 35 side by side behind it, said parts 34, 35 being desirably separated by a slit 36 cut through the paper strip. All these parts 33, 34, 35 of each section of the strip are marked identically as by the numbers ("499, 500, 501") printed thereon indicated in Figure 14. This strip is wound on a drum 37 turnable on a spindle 38 extending through the hollow shaft 18 and having a threaded inner end 39 turned at 40 into the inner side 41 of the housing 20, and having also a knurled handle 60 for unscrewing the spindle 38 to remove the same so that the drum may be withdrawn (the cover 43 being opened) to apply to the drum new rolls of paper strips.

The hollow shaft 18 has a key pin 44 engaging in the drum to rotate the same and the drum 20 has a radial slot 61 receiving shaft 18 so that the drum may be moved upwardly sidewise out of the housing. A sleeve 45 is keyed at 46 to the hollow shaft. A gear 47 is rotatable on this sleeve and has a pawl 48 engaging the teeth 49 of its hub portion 50 (Figure 13). A toothed rack 51 parallel with rack 30 and movable with the gate 2 meshes with this gear 47 to rotate the same and the drum in order to push the free end of the strip 32 through the slit 52 when the gate is drawn outwardly.

When this is done, the part 33 of the strip projects from said casing 20 and may be removed by the operator, but the rearward parts 34, 35 of the same section of the strip are severed therefrom by a cutter blade 53 (Figure 6) whose carrying lever 54 is fulcrumed at 55, this blade being forced downwardly against pressure of a spring 56, to sever said parts 34, 35, by the cam arm 57 of said lever striking the part 58 of the rack 51 when the gate is drawn to its outermost position. These parts 34, 35 of the strip when thus severed fall on opposite sides of a pointed partition 59 so that part 34 falls through a passage 62 into the bag 6 with the mass of the grain, while part 35 falls through a passage 63 into the can or receptacle 15 with the grain samples (Figure 5).

The hollow shaft 18 has handle wings 42 for manually turning the same.

The receptacle for the grain samples, designated generally 15, with its various parts is illustrated in Figures 7, 8, 9, 10, 11, 12. This receptacle comprises the vessel or can 64 desirably of glass having a metal top or cover 65 screwed on its open upper end as shown in Figure 8. This cover has a flat horizontal metal plate 66 bifurcated at 67 to slip over and straddle the downwardly extending neck portion 68 of the chute 9 (communicating with its discharge opening 13 as seen in Figures 7 and 8) to removably mount the receptacle in place. Said cover has inside it a parallel plate 69 on which is centrally pivoted at 70 a parallel shutter plate 71. The cover and the shutter plate and the plate 69 have round openings 72, 73, 74 respectively in registration with said opening 13 in the operative position of the mechanism shown in Figure 8, so that the grain samples may fall from the chute into the can 64.

The shutter plate 71 has an arcuate slot there-through comprising a first portion 75 of greater radius and a second portion 76 of less radius connected by a radial portion 77. The portion 75 has at its end an inwardly radial extension 78 and an outwardly radial extension 79, and the

portion 76 has at its end an inwardly radial extension 80.

A latch 81 pivotally mounted at 82 on plate 69 extends upwardly through said arcuate slot and through a slot 83 in the cover 65. Before the cover is screwed on the can 64 the shutter plate 71 is turned so that this latch engages in extension 78 of slot portion 75 as shown in Figure 10, so that the shutter plate is held in the position there shown in which its opening 73 is not in registration with the cover's opening 72. The cover being now applied to the can the receptacle is mounted on said neck portion 68 and as the bifurcated plate 66 is pushed to its limited inward position shown in Figures 7 and 8, the extremity 84 of said neck portion's outwardly extending horizontal portion 85 strikes the upper end of said latch as shown in Figure 8 and turns it against its spring 86 out of extension 78 and into the main part of portion 75 of the arcuate slot so that the spiral spring 87 is permitted to turn the shutter plate to bring its opening 73 into registration with openings 72 and 74 as seen in Figure 8 in order that the grain may run into the can. This turning movement of the shutter plate is stopped by the side 88 of the slot's portion 77 striking the latch, and the shutter plate is held in this position during the filling of the can.

When the receptacle is filled sufficiently, it is withdrawn from the neck's extension 85, and the latch's spring 86 draws the latch out of the arcuate slot's portion 77 and into its portion 76 whereupon the spiral spring 87 is permitted to further rotate the shutter plate to the position seen in Figure 11 wherein its opening 73 is not in registration with the cover's opening 72 and the can is thus sealed. This second turning movement of the shutter plate is stopped by the upwardly turned end 89 of a spring latch 90 engaging in the extension 78 of portion 75 of the arcuate slot.

The can 64 and cover 65 may be secured together with seals of any common form (not shown) which must be broken to remove the cover. When the cover is removed, the spring latch 90 may be released by drawing its pin handle 91 downwardly (Figure 12).

The invention being intended to be pointed out in the claims, is not to be limited to or by details of construction of any particular embodiment thereof illustrated by the drawings or hereinbefore described.

I claim:

1. Mechanism for withdrawing samples of a mass of grain or the like passing through a discharge spout, comprising: a chute for the samples having an inlet from the spout; a gate valve normally closing the spout and the chute and openable to permit the mass of the grain to pass outwardly through the spout and a less amount of the grain as samples thereof to simultaneously pass outwardly through the chute; a conveyor for feeding the samples through the chute; means for initiating the operation of the conveyor by the opening movement of the valve.

2. Mechanism for withdrawing samples of a mass of grain or the like passing through a discharge spout, comprising: a chute for the samples having an inlet from the spout; a valve normally closing the spout and the chute and openable to permit the mass of the grain to pass outwardly through the spout and a less amount of the grain as samples thereof to simultaneously pass outwardly through the chute; a conveyor for feeding the samples through the chute; means for

- initiating the operation of the conveyor by the opening movement of the valve; means for rotatably mounting a paper roll comprising successive sections each section having separable parts displaying identical markings; means operable by the movement of the valve for projecting the free end of the roll and for separating said parts; means for depositing said parts in the spout and chute respectively.
- 10 3. In combination: a chute for samples of grain or the like; a valve normally closing the chute and openable to permit the samples to pass outwardly through the chute; a receptacle for the samples adapted to be removably mounted on the chute at its outlet and having a turnable valve plate with an opening therethrough initially out of registration with said outlet, a spring urging said plate to a turned position wherein said opening and outlet are in registration to permit passage of the samples therethrough into the receptacle; a latch releasably holding the plate in such non-registering initial position and movable to release said plate by the engagement of the latch with a portion of the chute in the mounting movement of the receptacle thereon.
- 15 4. In combination: a chute for samples of grain or the like; a valve normally closing the chute and openable to permit the samples to pass outwardly through the chute; a receptacle for the samples adapted to be removably mounted on the chute at its outlet and having a turnable valve plate with an opening therethrough initially out of registration with said outlet, a spring urging said plate to a turned position wherein said opening and outlet are in registration to permit passage of the samples therethrough into the receptacle; a latch releasably holding the plate in such non-registering initial position and movable against a spring to release said plate by the engagement of the latch with a portion of the chute in the mounting movement of the receptacle thereon and to releasably hold the plate in such registering position, the latch being releasable from its position wherein it holds the plate in such registering position by withdrawing the receptacle from its mounted position thus disengaging the latch from
- 20
- 25
- 30
- 35
- 40
- 45

the chute and thereby permitting the farther turning movement of the plate to a position wherein its opening is again out of registration with said outlet.

5 5. In combination: a chute for samples of grain or the like; a valve normally closing the chute and openable to permit the samples to pass outwardly through the chute; a receptacle for the samples adapted to be removably mounted on the chute at its outlet and having a turnable valve plate with an opening therethrough initially out of registration with said outlet, a spring urging said plate to a turned position wherein said opening and outlet are in registration to permit passage of the samples therethrough into the receptacle; a latch releasably holding the plate in such non-registering initial position and movable against a spring to release said plate by the engagement of the latch with a portion of the chute in the mounting movement of the receptacle thereon and to releasably hold the plate in such registering position, the latch being releasable from its position wherein it holds the plate in such registering position by withdrawing the receptacle from its mounted position thus disengaging the latch from the chute and thereby permitting the farther turning movement of the plate to a position wherein its opening is again out of registration with said outlet; a manually releasable latch for holding said plate in a position wherein its opening is out of registration with said outlet.

10 6. Mechanism for withdrawing samples of a mass of grain or the like passing through a discharge spout, comprising: a chute for the samples having an inlet from the spout; a valve normally closing the spout and the chute and openable to permit the mass of the grain to pass outwardly through the spout and a less amount of the grain as samples thereof to simultaneously pass outwardly through the chute; a conveyor for feeding the samples through the chute; a spring for operating the conveyor; connections between the valve and the spring for tensioning the spring by the opening movement of the valve.
